UNITED STATES PATENT OFFICE

2,509,464

CONTINUOUS WOOL SCOURING APPARATUS

George Charles Weinpel, Clifton, N. J., assignor
to Botany Worsted Mills, Passaic, N. J., a corporation of New Jersey

Application January 24, 1947, Serial No. 724,204

3 Claims. (Cl. 68—158)

1

The object of the present invention is to provide an apparatus for wool scouring which will greatly reduce the damaging chemical and mechanical effect upon the wool by the processes and apparatus generally in use, which will reduce the production of noilage, and which will result in a greater recovery of wool grease and its valuable constituents. By means of my apparatus the wool may have a markedly lower over-all alkalinity treatment than heretofore and yet with improved scouring, so that the wool treated by the process is superior. Furthermore, an increased rate of scouring is obtained, since the time of treatment in the successive bowls is substantially reduced.

The invention will be described with reference to the accompanying drawings, in which.

Fig. 1 is a view in elevation showing an initial scouring bowl and certain devices operatively appurtenant thereto part of a succeeding bowl being shown.

Fig. 1a is a plan view of the structure shown in Fig. 1.

Fig. 2 is a continuation of the assembly shown in Fig. 1, and in elevation.

Fig. 2a is a plan view of the assembly shown in Fig. 2, but partly broken away.

Fig. 3 is a continuation of the assembly shown in Fig. 2, and in elevation.

Fig. 3a is a plan view of the assembly shown in Fig. 3.

Fig. 4 is a view in elevation showing the assembly of wash liquor treatment and grease recovery units.

Fig. 5 is a plan view of the assembly shown in Fig. 4, three of the tanks having been turned at right angles from their position as shown in Fig. 4.

Fig. 6 is a fragmentary view in vertical section and somewhat enlarged, showing the receiving end of the initial bowl, the latter being partly broken away.

Referring to the drawings, it will be seen that Figs. 1 and 1a show the initial scouring bowl 1 in conjunction with appurtenant units which include a wool delivery device 2 into which the raw wool is fed from a chute 3, the wool being carried upwardly by a spiked apron 4 and brushed off by a rotating member 5, the wool being dropped to the chute-like end 2a of the delivery device and thence delivered to tray 6 at the bottom of which is an apron 7 which carries the wool to a compartmentized rotary drum 8 from which the measured wool is dumped onto a pin-carrying open mesh or chain conveyor belt 10 in bowl 1.

2

Near the bottom of bowl 1 is a screen 9 and running parallel therewith is the lower length of the belt 10. This belt, as shown in Fig. 5, carries transverse rows of wool-feed pins 11. On its lower length the belt pins project downwardly close to the screen 9, and the belt is driven at synchronous speed with the drum 8 and moves to the left of Fig. 1 over a driving sprocket or drum 12, thence horizontally to a guide pulley 13, thence out of the bowl 1 and above the same, over spaced guide pulleys 14, and thence by downwardly inclined arrangement it passes into the bowl and under a guide pulley 15 to form the lower horizontal belt length.

15 The section of the belt led out of the bowl 1 at its rear dumps the wool upon a compartmentized drum 8a which in turn discharges the wool into a second bowl 1x which is of the same construction as the first bowl and hence the elements thereof are given the same numerals in the drawings.

16 Each of the bowls 1 and 1x is provided, below screen 9, with a plurality of triangular hoppers 16, and at the base of each hopper is a displacement pump 17 connected by a pipe 18 to a manifold 19 at the top of a settling tank 20. The manifold 19 discharges into a depending pipe 21 onto a deflection plate 22 and the rising liquid is subjected to the action of a plurality of baffles 23 within the settling tank, and in this manner the heavier sediment tends to drop to the base of the bowl to be drawn off by a valve controlled discharge conduit 24.

25 When the wool reaches the horizontal length of feed belt 10 at the discharge end of tank 1, and also at the discharge end of bowl 1x, it receives a spray of hot wash water or liquor from a spray device 25, and the action of the latter is supplemented by a suction trough 26 which lies immediately below the belt, so that part of the wash liquor carried upward by the wool, and the rinse water or liquor is drawn into the suction trough from which it is pumped by pump 27, as to each bowl 1 and 1x, to the manifold 19 and hence to the settling bowl. Thus the hot spray and suction devices 25, 26 serve to remove loose foreign matter in the wool delivered by bowl 1 to bowl 1x, and from the wool delivered by the latter bowl to a succeeding bowl, the latter being hereinafter described as to its function and elements.

40 Variability in the amount of liquor drawn off from each of the bowls 1 and 1x is secured, because there is a variable displacement pump for each hopper. The liquor thus subjected to the 45 action of the settling tank 20, the latter remov-

ing much of the foreign matter from the emulsified liquor containing the valuable wool grease, is delivered to a surge tank 28 via pipe 29, the latter being valve-controlled. Well above the base of the surge tank is an outlet pipe 30 connected to a pump 31 by means of which the liquor may be pumped through a steam jacketed temperature control unit 32 which may receive and discharge circulated steam or hot water via the pipes 33. The liquor is then drawn into a centrifugal extractor 34 by means of which a large percentage of dirt and foreign matter is removed and discharged into a pipe 35 which leads to a manifold pipe 36. The latter also receives sediment from the surge tank 28 and the base of the latter may have connected thereto a pipe 35x controlled by a valve 37, it being preferred that a pump 38 be applied to pipe 35x, the latter discharging into manifold pipe 36.

By this time the liquor is nearing a final cleansing, and is transferred by pipe 39 and branch pipes 40 to a plurality of precipitation or treatment tanks 41, 42, 43. These tanks enable one tank of liquor to undergo treatment while one is being filled and while the treated liquor from a third tank is being led to a centrifugal extractor or other device for further treatment. The liquor in said treatment tanks 41, 42 and 43, may receive a suitable chemical precipitant and the foreign matter collected at the base of each tank may be removed from time to time. The branch pipes 40 are controlled by valves 44 and the treated liquor is discharged through pipes 45, controlled by valves 46, to a pump 47 which discharges into a centrifugal separator 48 for further dirt removal.

From the centrifugal unit 48 the liquor passes to a collection tank 49 from which it is pumped to a constant head tank 50 which contains a heating coil 51 for maintaining the desired temperature. The constant head tank 50 feeds to a set of centrifuges 51 which discharge the purified and light wool grease with minor liquor to outlet pipe 52 which feeds into the lower level storage tank 54. The major volume of liquor and the small remaining dirt pass as tailings through pipes 51x to a draw-off manifold pipe 53.

The said tailings from the centrifuges 51 flow from pipe 53 to a set of treatment tanks 55, 56 and 57, the flow into these tanks being controlled by valves 58. These tanks may be used in the manner of tanks 41 to 43 inclusive, and by means of valve-controlled pipes the sediment from the two sets of tanks, that is to say set 41 to 43 and set 55 to 57, may be drawn off to a discharge pipe 59. The sediment flow from tanks 41 to 43 is via valve controlled pipes 59x.

It will be seen that the liquor led to the tanks 55 to 57 inclusive has been greatly cleansed and removed of substantially all wool grease, and also that by settling, aided by a chemical precipitation, if necessary, the liquor will be clarified and made excellent as scouring liquor. It will also be seen that the said tanks may be selectively used in the transfer of scouring liquor to an appropriate bowl or bowls. This follows because there is provided for each tank 55, 56 and 57, a valve controlled discharge pipe 55x, 56x or 57x, as the case may be, leading to a manifold conduit 60 through which the scouring liquor may be pumped by pump 61 to a jacketed heater 62 to which and from which a heating medium may be passed by pipes 63, the heated scouring liquor being led to a discharge pipe 64 and thence to feed or spray pipes 65 delivering to the tanks 1 and 1x. Spray

pipes are preferred and the spray will be delivered directly upon the wool in its movement along the top of the tanks. The spray at 25 also may have at its source the liquor from one or all of the treatment tanks 55 to 57, in accordance with desired operation of control valves for said tanks.

In practice, one of the tanks 55, 56 or 57, will be employed for alkalinity control of the wash liquor led to tanks 1, 1x, although all three tanks 10 may be so used.

It will be seen from the above that the wash liquor treatment and wool grease units above described are fed from the bi-unit bowl assembly 1, 1x. The function and appurtenant elements of 15 the succeeding bowls will now be described.

Reference to Figs. 2, 2a, will show that bowl 1x discharges wool therefrom into a succeeding bowl 66, and that the latter discharges into a companion bowl 66x. These bowls and their 20 appurtenant elements, including wool feeding means, sprays and suction devices, hoppers, pumps and settling tank are of the same construction and arrangement as with bowls 1, 1x and therefore the same reference numerals are 25 used in the drawings.

The top discharge pipe 29 of the settling tank for bowl units 66, 66x will lead to the surge tank of a wash liquor area treating and wool grease recovery assembly the same as that of Fig. 5, 30 and the operation is the same, so that further description is unnecessary.

Reference to Figs. 3, 3a, will show that bowl 66x discharges wool therefrom to a bi-unit rinsing bowl assembly consisting of the bowls 67, 67x. 35 These bowls also, and their appurtenant elements, with the exception that they may omit a settling tank, are the same as with the preceding bowls, and the same reference numerals are employed. At the discharge end of bowl 67x the cleansed 40 wool will be led to a discharge conveyor indicated at 68. A continuous flow of rinse water may be led to bowls 67, 67x via pipes 69, 70.

Raw wool contains various foreign substances, such as dirt, particles of organic nitrates, vegetable 45 matter including leaf and bur particles, sulfur and other chemical substances from sheep dip, etc. In the method of scouring commonly employed it has been considered necessary to employ a scouring bath or baths of relatively high 50 alkalinity with a pH of 9.8 to 11 for a time exceeding 10 minutes for each operation and a temperature not above 120-130° F. a higher temperature being damaging to the wool at such alkalinity of the bath. The wool is slowly moved 55 through the baths by forks, either crank operated or on an endless belt, generally in such manner when a belt was used, that the lower length moves the forks against the wool on the screen whilst the upper length acts as a return idler above the 60 bath. The screen lies in the bath immediately below the moving wool in such generally used method, and periodically dirt and sediment is removed from the area below the screen. The wool is passed from one bath to another via 65 squeeze rolls, and in a refinement it has been advocated that the wash liquor within the bowls be pumped from bowl to bowl in a direction reverse to the direction of travel of the wool with the object that a high proportion of the wool 70 grease be carried back to the initial bowl and there discharged to a drain communicating with the upper area of the wash liquor. In all of the said present methods the wool is subjected for long periods to a high alkaline wash liquor, the 75 wool grease is permitted to build up in volume

within the bath, there is a chemical effect on the wool which results in an average noilage of 12 to 15%—a result which heretofore has been considered normally incident to wool scouring, the optimum good "feel" of the wool has not been maintained, the rate of scouring has been very slow as compared with that of my method, and the amount of soda ash and soap employed has been very much larger.

The method of operating my apparatus will now be described in particularity. Its characteristics are:

- (a) Subjecting the raw wool initially and in progressive movement in an elongated path to a wash bath of high temperature, which may be 120°-200° F., and thus higher than the maximum temperature of the method now in use, it preferably is at or near the upper limit, said bath is of neutral or very low alkalinity, the period of time, 5-15 minutes, being relatively short but sufficient to remove all but a minor proportion of the wool grease.
- (b) Utilizing by the high heat of said initial bath the natural organic salts present in the wool, to act as detergents in releasing dirt and wool-foreign substances and to aid in releasing the wool grease.
- (c) Separately withdrawing by pump force action, from a plurality of zones along the elongated path of the bath and at the base thereof, settled dirt-and-wool-grease-carrying wash water.
- (d) By means of a plurality of settling and centrifugal-filter operations separately removing purified wool grease and clarified wash liquor from the dirt and wool-foreign substances, and returning the clarified wash water to and at the temperature of the bath, but usually at such higher temperature as to compensate, at least in part, for heat losses in the bath.
- (e) Subjecting the wool, thus removed of its major grease and much dirt, to a lower temperature similarly elongated bath of alkaline wash liquor, for a time equivalent to that of the first bath and said alkaline bath may have a pH less than customarily employed for wool washing, a pH of 7.6-7.8 being operative, the operative temperature being 120-150° F., and preferably at or toward the upper limit.
- (f) Withdrawing from separate zones of the said elongated alkaline bath area, and at the base thereof settled dirt-and-wool-grease-carrying wash liquor, and treating it separately from that of the first bath but in the manner of (c), the clarified wash liquor being returned to the bath after adjustment of its alkalinity.
- (g) Subjecting the thus cleansed wool to a rinsing bath which may be of 110° F.
- (h) Intermediate the washing zones, and also preliminary to rinsing, withdrawing the wet wool from its then bath and subjecting it to a hot wash spray and to suction, before it meets the succeeding bath, resulting in the removal of loose foreign matter, and the avoidance of squeeze rolls which induce noilage.

There is no intermittent plunging action of rakes on the wool as in the commonly used vertical lift and drop rake feeds. The spaced transverse rows of pins in the conveyors are spaced in

accordance with the compartments of the compartmentalized drums, and the drums and conveyors travel at the same speed so that as the wool is transferred from bowl to bowl it remains in its initial volume but in changed position for uniform scouring. The wool is base supported by the conveyors, not by the screens, the conveyors including open mesh wire cloth or equivalent elements, for such support. The feed is such that the movement of the wool is through the top portion only of each scouring bath, thus enabling ideal settling of sediment in a relatively undisturbed and deep area above the screen as well as in the hoppers below the screen.

- 10 15 In the above stated characteristics of my method it should be understood that the initial bath comprises that of the first two bowls 1, 1x, and the "alkaline" bath that of the two bowls 67, 67x. This enables continuous withdrawal of wool from the two zones of the initial bath of highly heated wash liquor for spray washing and suction, and like withdrawal and action upon wool from the two zones of the second and "alkaline" bath.
- 20 25 Having described my invention, what I claim and desire to secure by Letters Patent is as follows:

- 1. In apparatus for wool scouring, a bowl for wash liquor, a compartmentalized conveyor longitudinally extending in said bowl and adapted for free flow of wash liquor through its compartments, a compartmentalized feeder for discharging wool into the compartments of the conveyor, the feeding length of the latter being confined to an upper area of the bowl whereby a lower area of the bowl is provided as an initial settling area, and a plurality of force feed means for withdrawing preliminary settled dirt-and-wool-grease-carrying wash liquor from a plurality of zones at the base of the bowl.
- 30 35 40 2. Apparatus for wool scouring constructed in accordance with claim 1, the conveyor having an upwardly extended feed length adapted to discharge into a second bowl, and wash spray and suction means adapted to provide a force flow of wash liquor through the wool passing in said upwardly extended length.
- 3. Apparatus for wool scouring constructed in accordance with claim 1, the conveyor having an upwardly extended feed length adapted to discharge into a second bowl, a second conveyor in the said second bowl, and a plurality of force feed means for withdrawing settled dirt-and-wool-grease-carrying wash liquor from a plurality of zones at the base of the said second bowl.
